UNITED STATES PATENT OFFICE

2,460,449

VISIBLE CARD INDEX

Robert J. Copeland, Toronto, Ontario, Canada

Application April 21, 1945, Serial No. 589,523

3 Claims. (Cl. 129—18)

1

This invention relates to improvements in visible index cards which are adapted to be placed in a holder in echelon arrangement and the principal objects are to provide cards each formed with a series of notches adapted to engage with positioning members arranged in fixed positions in a card holder, said notches being engaged by movable members mounted in the card holder and adapted to lock the cards against accidental displacement whether in normal or reversed positions.

A further important object is to devise a card holder with regularly spaced positioning members to engage notches in the cards to accurately locate same to hold them in their relative positions and also having a slideable member carrying locking members adapted to be readily moved to locking or release positions to hold or release the cards.

The principal feature of the invention consists in the novel construction of a card holder with regularly spaced fixed transverse members and a slideable frame arranged thereabove having regularly spaced transverse members, and cards having T-shaped slots, the lower portion of which is adapted to engage said fixed members for positioning the cards in the holder relative to each other and the upper portion presents shoulders to engage the transverse members of the slideable member to lock the cards from accidental displacement.

In the accompanying drawings Figure 1 is a longitudinal vertical section of one end portion of a card holder constructed in accordance with this invention showing the locking cross members in position with the cards unlocked.

Figure 2 is a longitudinal vertical section of the end of a card holder opposite to the end shown in Figure 1 and showing the locking cross members in the position to lock the cards in place.

Figure 3 is an enlarged fragmentary longitudinal section of a card holder showing the card locking members in the locking position.

Figure 4 is an enlarged fragmentary perspective view of a portion of the card holder shown in Figure 2.

Figure 5 is a cross section through the card holder as shown in Figure 4.

Figure 6 is a cross section through a card holder showing a slightly modified construction.

Figure 7 is an enlarged fragmentary longitudinal section of a card holder as illustrated in Figure 6 showing the locking members in the position to lock the cards.

Visible index cards in which the record cards

2

are arranged in groups in echelon are found to be a highly desirable form of keeping records of various kinds and it is common practice to form such cards with a plurality of equally spaced notches in the bottom edge which fit over rods arranged transversely of a case for holding such cards, thereby assuring the edge spacing of the cards so that groups thereof may be kept in echelon arrangement to display the index tabs or the diagonal upper corners thereof.

Such card holders sometimes are upset and the cards become misplaced in such a manner that a great deal of labour is involved in putting the cards in order.

This invention has been devised to provide a very simple and economical means for preventing such accidental displacement of the record cards.

20 In the form of the invention illustrated herein the card holder is formed of a length 1 of sheet material, preferably steel. The longitudinal edges 2 are turned at right angles forming a shallow U-shaped metal strip. The strip 1 is preferably backed by an outer cover 3 with flanged edges 4, which may be formed of card or suitable fibre board.

Side covers 5 of suitable form and material are hinged to the longitudinal side flanges 2. The 30 outward swing of these covers may be limited by links 6 slidably connected to a slotted end plate 7.

Mounted transversely of the member 1, and 35 equally spaced throughout the length thereof are a plurality of cross ribs 8 here shown of flanged sheet metal which may be riveted, spot-welded or otherwise secured. These cross ribs 8 register with notches 9 cut in the bottom edge of the record cards 10 and said notches are preferably arranged so that every fourth notch will 40 register with one of the cross ribs 8. This arrangement provides a desired spacing for the overlapping echelon arrangement of the cards.

Each of the notches 9 is formed in T-shape, that is to say, each vertical edge of the notch is 45 formed with a lateral enlarged part 11 at the top thereof.

A rectangular frame 12 formed of a narrow strip of material, preferably steel, is slidably arranged on the inward side of the U-shaped bar 1 and is secured in position by screws or rivets 13 50 extending through longitudinal slots 14 and secured in the side flanges 2.

At one end, the frame 12 is narrowed and the cross member 15 thereof is engaged by the slotted 55 end lugs 16 of a finger plate 17 which is pivotal-

ly supported on a cross bar 18 secured at the ends in the side flanges 2 of the member 1.

It will be understood that by pressing inwardly upon the finger plate 17 it will be swung on its pivotal support and the slotted lugs engaging the cross bar 15 of the frame 12 causes said frame to be moved longitudinally. An opposite movement of the frame is effected by pressing outwardly on the upper edge of the finger plate.

A plurality of cross bars 19 are secured in the longitudinal side members of the frame 12 and extend between the same. These cross bars are arranged to register with the cross ribs 8 and are arranged slightly above the top edge of said ribs when the finger plate is in the outward position.

The cross bars 19 are adapted, when the finger plate is pressed inwardly, to move laterally to one side of the upper notched portions 11 of the cards 10, as illustrated in Figures 2 and 3, and it will be seen that when these cross bars are in this position the cards, which are held from shifting longitudinally by the cross ribs 8 extending into the central openings of the T-shaped notches, will prevent the cards from being lifted out of the holder, or from being accidentally displaced if the holder is upset.

When it is desired to remove cards from the holder for the purpose of making entries thereon the finger plate is pressed outwardly to shift the cross bars 19 to the position as illustrated in Figures 1 and 4 so that they will be moved clear of the shoulders formed by the enlarged portions 11.

The notches 9 are formed T-shaped so that if the cards are reversed and have entries made on the reverse side the locking of the cross bars 19 will still be effective.

The device herein described is capable of various modifications, and as shown in Figures 6 and 7, in place of the rib members 8 being secured to the metal strip 1, cross bars 20 may be arranged to extend between the side ribs 2 to enter the lower portion of the T-notches 9. When this construction is adopted, the frame 12 may be arranged above the cross bars 20 or the frame may be slotted to permit the frame to slide longitudinally.

It will be understood from this description that the present invention is extremely simple to construct and it will also be strong and serviceable.

What I claim as my invention is:

1. In a visible card index, cards having spaced notches in the edge, each notch having a laterally enlarged portion, a holder to receive said cards having cross members to enter the notches and engage the sides thereof to position said cards, and locking means adapted to enter said notches and being movable longitudinally of said holder

above said cross members to enter the laterally enlarged portions of said notches.

2. A card index comprising, a holder having flanged edges, spaced ribs extending transversely of said holder between said flanged edges, bars slidably arranged parallel with the flanged edges of said holder, cross bars arranged above said ribs and having their ends secured in said slideable bars, said cross bars being spaced equal to the spacing of said cross ribs, means for moving said slideable bars to move the cross bars into and out of vertical register with the cross ribs, and cards formed with notches spaced to register with the cross bars and ribs, said notches having enlarged portions at the top to permit displacement of the upper cross bars from out of vertical alignment with the holder cross ribs.

3. A card index comprising, a longitudinal strip formed with edge flanges, cross ribs equally spaced extending across said longitudinal strip, a frame slidably arranged between the flanges of said longitudinal strip, cross bars arranged in said frame above said cross ribs but spaced equally thereto, means for moving said frame longitudinally of said strip to move said cross bars into and out of vertical register with said cross ribs, and cards having in their lower edge notches of T-form adapted to receive the cross bars and cross ribs when in register to position the card and to permit lateral movement of the cross bars above the cross ribs to lock the cards securely in position.

ROBERT J. COPELAND.
